UNITED STATES PATENT OFFICE.

FREDERICK W. HODGES, OF DETROIT, MICHIGAN, ASSIGNOR TO DETROIT LUBRICATOR COMPANY, OF DETROIT, MICHIGAN, A CORPORATION OF MICHIGAN.

DEVICE FOR LUBRICATING CAR OR LOCOMOTIVE WHEELS.

1,170,752.

Specification of Letters Patent.

Patented Feb. 8, 1916.

Application filed June 24, 1914. Serial No. 846,912.

To all whom it may concern:

Be it known that I, FREDERICK W. HODGES, a citizen of the United States of America, residing at Detroit, in the county of Wayne 5 and State of Michigan, have invented certain new and useful Improvements in Devices for Lubricating Car or Locomotive Wheels, of which the following is a specification, reference being had therein to the 10 accompanying drawings.

My invention relates to a device for feeding oil upon the flange of a car or locomotive, the same being normally inoperative but adapted to feed by and upon the vibrations which arise when the vehicle is in motion.

It consists in means operated by the vibration of the vehicle to positively feed the oil upon the flange, and in the construction 20 and arrangement of the parts so that the drip of the oil between feeding actuations of the device is eliminated or minimized; and in the construction, combination and arrangement of the various parts as herein- 25 after set forth and particularly pointed out in the claims.

In the drawings: Figure 1 is a vertical central section through the oil supply tank, and with the pump therein, of the preferred 30 form of my device; also showing in section the discharge nipples at the wheels; Fig. 2 is a section on line $\alpha-\alpha$ of Fig. 1; Fig. 3 is a side elevation looking from the right-hand of Fig. 2; and Fig. 4 is an enlarged 35 section through one of the discharge nipples.

At the present time it is well understood that to apply lubricant to the flanges of locomotive driving wheels very materially lengthens the service or life of the driving 40 surfaces thereon, and a number of devices have been used to effect this lubrication. Condensation displacement oil feeding devices having a discharge pipe leading to the wheel, with steam blowing through the pipe 45 to spray the oil upon the flange, have been employed; spring-pressed graphite sticks have also been applied to the wheel; and it has also been proposed to have an oil tank with gravity feed, the outlet therefrom being controlled by a valve, said valve to be 50 operated by a rolling ball, the ball being set in motion by the vibration or oscillation of the locomotive.

Any device which feeds the oil constantly

is objectionable because it will feed the oil 55 while the locomotive is standing still and any surplus of oil upon the wheels will be transmitted to the track and very greatly reduce, if not entirely eliminate, the traction. The rolling ball construction for operating the valve lacks sensitiveness and depends upon gravity for feeding, and the dust and dirt will accumulate in running and will fill up the discharge orifices and may render the device inoperative. In the devices in 60 which an unobstructed feed pipe is used, from the oil tank or feeding device to the wheels, when the locomotive stops the oil continues to drip until the pipe is empty, and thus feeds the oil unnecessarily and reduces the traction when it is most needed.

My device overcomes the objections to these prior devices, is extremely sensitive in operation and efficient in the delivery of oil when most needed and stops feeding 75 whenever the train comes to rest.

A represents an oil tank in which I have shown four cylinders, B B'. These cylinders have an intake-nipple, a, controlled by a check-valve, b, and a discharge port, c, controlled in this instance by a spring-pressed check-valve, d. At the lower end I have shown these cylinders each as resting upon the bottom of the tank and held in position 80 therein by a flanged nipple, C, passing through the tank and clamping the parts tightly together. In each of the cylinders B B' are pistons, D D'. In the upper end of each of the pistons I provide a vertical slot, E, and projecting into the end of the pistons 85 is a set screw, F, its lower end forming the upper end of the slot and thus forming means for adjusting the length of the slot.

A rock-shaft, G, is shown as journaled in the upper portion of the tank A, provided 90 with sleeves, H, having laterally projecting rock-arms, I, I', at opposite sides, which pass through the slots in the pistons D D'. The sleeves H may be detachably secured to the rock-shaft as by set-screws, J. The rock-shaft G preferably extends through the wall 100 of the oil tank and is provided with a pendulum, O, having a weight, P, preferably adjustably secured thereon, as by the set-screw Q. Discharge pipes, K, K', communicate with the discharge passages through the nipples, C, leading to a point in proximity to the wheels, L, to be lubricated. At the ends of 105

the pipes, K K', are check-valves, M, M'. In this case I have shown secured to the ends of the pipes K K' discharge nipples, R, connected with the ends of the pipes by means 5 of a ball-and-socket joint, as shown at S, and having within an adjustable drip pin, T, leading into close proximity to the flange of the wheel where the oil is to be deposited, the pin T being of smaller diameter than 10 the nipples, R, so that the oil may freely pass out and flow down the pin and drip upon the wheel at the desired point. This construction of discharge nipple forms no part of my present invention, and any other 15 means may be employed for bringing the oil upon the wheel at the desired point, or the pipes K K' may terminate in close proximity to these wheel flanges.

It is obvious from the description of the 20 mechanism that as the locomotive travels over the track there is more or less oscillation or vibration imparted to it, and such oscillation or vibration will cause the weighted pendulum, P, to swing and the 25 swinging thereof will rock the shaft G and rock arms I I' thereon and raise and lower the pistons D D' in the cylinders B B' and draw oil in through the inlet opening and discharge it through the discharge port into 30 the pipes K K'; and when those pipes have been filled the further movement of the pump will unseat the valves M M' and cause the oil to drop or flow upon the wheel flanges.

35 With the construction shown, in which there are four pumps, the oil will be fed to the four drivers, two upon each side, or to any other wheels desired. It is also obvious that when the locomotive is at rest there will 40 be no motion imparted to the pendulum and no oil will be fed. By having the check-valves, or other arresting means, immediately adjacent the point to which the oil is to be delivered, as soon as the device stops 45 forcing the oil supply to the wheels will be stopped and only the oil below the check-valve will drip upon the wheels,—which will be an entirely negligible quantity.

The pendulum device for controlling the 50 oil feed is exceedingly sensitive and by adjusting the screws F vertically and also by adjusting the weight P on the pendulum O, it may be adjusted to any desired feed.

By having the forced feed for feeding the 55 oil the danger of stoppage by clogging at the discharge end of the delivery pipes is practically entirely eliminated.

60 While the construction herein shown is the construction which I prefer to employ, it is obvious that it may be varied in many ways without departing from the spirit of my invention.

65 While I have shown the device as delivering oil to lubricate the wheel flanges, it is obvious that the point of delivery is imma-

terial so far as my invention is concerned, and that it can be used for delivering oil at other points of the vehicle.

What I claim as my invention is:

1. In a device for lubricating car or locomotive wheels, the combination of a lubricant pump carried on the vehicle and means for actuating the pump by the vibration of the vehicle operative at all the normal angles at which the vehicle travels. 75

2. In a device for lubricating car or locomotive wheels, the combination of an oil tank, a pump for taking the oil therefrom and delivering it to the wheel, and a device actuated by the vibration of the vehicle for 80 operating the pump operative at all the normal angles at which the vehicle travels.

3. In a device for lubricating car or locomotive wheels, the combination of an oil tank, a pump for taking oil therefrom and 85 delivering it to the wheel and a pendulum connected to the pump and oscillated by the vibration of the vehicle and operating the pump substantially without lost motion.

4. In a device for lubricating car or locomotive wheels, the combination of an oil supply vessel, a pipe leading therefrom to the wheel and a pendulum device normally inoperative and operated by the vibration of the vehicle in motion for controlling the flow 95 of oil to the wheel at all normal angles at which the vehicle travels.

5. In a device for lubricating car or locomotive wheels, a force feed device for delivering the oil upon the wheel, normally 100 inoperative, and means for operating it by and upon the oscillation of the vehicle in motion operative at all the normal angles at which the vehicle travels.

6. In a device for lubricating car or locomotive wheels, the combination of a tank for lubricant, a pipe leading therefrom to the wheel, means for force-feeding the lubricant through the pipe and means for controlling the force-feeding means by the vibration of 110 the vehicle operative at all the normal angles at which the vehicle travels.

7. In a device for lubricating car or locomotive wheels, the combination of an oil supply, a pair of pumps taking the oil therefrom and delivering it to the wheels, and a single pendulum connected to the pumps, oscillated by the vibration of the vehicle for actuating simultaneously the suction stroke of one pump and the pressure stroke of the 120 other.

8. In a device for lubricating car or locomotive wheels, the combination of an oil supply tank, a rock-shaft therein, a rock arm on said shaft, a pump actuated by said 125 rock arm for taking the oil from the tank and delivering it to the wheel, and means for rocking said shaft by the vibration of the vehicle in motion.

9. In a device for lubricating car or loco- 130

- motive wheels, the combination of an oil supply tank, a rock shaft, a plurality of rock arms projecting from the shaft upon opposite sides, a pump connected to each 5 rock-arm for taking oil from the tank and delivering it to the wheels, and a pendulum device adapted to be actuated by the vibration of the vehicle in motion for rocking said shaft.
- 10 10. In a device for lubricating car or locomotive wheels, the combination of an oil supply vessel, a pipe leading therefrom to the wheel, a check valve adjacent the point of delivery, means for forcing the oil beyond 15 the check-valve, said means being operated by and upon the oscillation of the vehicle in motion operative at all the normal angles at which the vehicle travels.
11. In a device for lubricating car or locomotive wheels, the combination of a lubricant supply vessel, a pipe leading therefrom to the point to be lubricated, a check valve at or near the point of delivery of the oil and an intermittent force feed device for 25 feeding the oil, said force-feed device being operated by the vibration of the vehicle at all the angles at which it travels.
12. In a device for lubricating car or locomotive wheels, the combination of a lubricant supply vessel, a pipe leading therefrom to the point to be lubricated, a check-valve at the discharge end of the pipe and means 30 controlled by the oscillation of the vehicle at all angles at which it travels for forcing oil through said pipe beyond the check-valve.
13. In a device for lubricating the wheels of railway vehicles, a tank, a pump actuated by the vibration of the vehicles in motion operative at all angles at which the vehicle travels, for taking the oil therefrom and delivering it to the wheel, a discharge pipe for the pump and a check-valve in the pipe, adjacent the point of delivery.
14. In a device for lubricating car or locomotive wheels, the combination of a lubricant supply vessel, a pipe leading therefrom to the point to which the lubricant is to be applied, a pump connected to take lubricant from the supply vessel and force the same through said pipe, and means for actuating the pump by the vibrations of the vehicle in motion operative at all the normal angles at which the vehicle travels.
15. In a device for lubricating vehicles, 55 the combination of a lubricant receptacle, a lubricator pump to take oil from the receptacle and deliver it to the part to be lubricated, means for actuating the pump by the vibration of the vehicle in travel, which 60 means is connected to the pump so that it is operated by oscillations of any degree.

In testimony whereof I affix my signature in presence of two witnesses.

FREDERICK W. HODGES.
